UNITED STATES PATENT OFFICE.

WILLIAM E. HATHeway, OF BRIDGEPORT, CONNECTICUT.

BUCKLE.

Application filed February 24, 1923. Serial No. 620,872.

To all whom it may concern:

Be it known that I, WILLIAM E. HATHeway, a citizen of the United States, residing at Bridgeport, in the county of Fairfield and 5 State of Connecticut, have invented certain new and useful Improvements in Buckles; and I do hereby declare the following to be a full, clear, and exact description of the invention, such as will enable others skilled 10 in the art to which it appertains to make and use the same.

This invention relates to buckles of the character adapted for suspenders and similar articles, and relates more particularly to 15 improved means of securing the end of the tape or webbing to the floor of buckle frame by utilizing practically the major portion of the floor as means for anchoring the end of the webbing, and thus giving greater holding 20 capacity and a firmer grip on the webbing than the use of a series of individual teeth.

Referring to the accompanying drawings wherein the same numerals and letters of reference indicate like parts throughout the 25 several views:

Figure 1 represents a detail plan view of the blank of the buckle frame;

Figure 2 is a view of the frame showing sections of the floor of the frame elevated to 30 form the clamping means for the end of webbing;

Figure 3 is a view of the assembled buckle with the lever in open position and a broken section of webbing in readiness to be secured 35 to the floor of the buckle frame;

Figure 4 is a similar view showing the clamping feature of the floor pressed down upon the webbing to secure it firmly to the frame;

Figure 5 is an underside or reverse view of the assembled buckle showing a section of webbing anchored therein;

Figure 6 is an upper or obverse view of the assembled buckle showing a section of webbing anchored therein;

Figure 7 is a rear elevation of the assembled buckle;

Figure 8 is an end elevation of the assembled buckle secured to the webbing;

Figure 9 is an enlarged sectional view of the floor of the frame and webbing on line 9—9 of Figure 3;

Figures 10 and 11 are similarly enlarged views showing the floor sections shortened, 55 and

Figure 12 is a reduced view of the under-

side of the buckle frame showing a single floor section.

The blank comprising the buckle frame shown in Figure 1 consists of the floor 1 and 60 ears 2. The small perforations *a*, *b*, are formed in the floor to give the necessary clearance for the floor sections 3, 4, broken away from the main body of the floor as shown in Figure 2. These floor sections are 65 temporarily elevated to merge the smaller openings into the two larger openings 5 and 6, which large openings are separated by the bridge 7 integral with the floor. This bridge serves to keep the remaining narrow portions 70 1^a of the floor of the frame from separating.

The ears 2 are then bent at right angles to the floor with the common lever 8 journaled therein. The webbing 9 is inserted between the floor of the frame and the 75 lever with its end abutting the base of the upturned floor sections 3, 4, as shown in Figures 3 and 9, while the bridge 7 serves an additional purpose in preventing the end of the webbing passing through the enlarged 80 openings in the floor. In other words, were it not for this bridge, the end of the webbing would, in the haste of assembling the same to the buckle, be more than liable to pass through an opening extending the full 85 length of the floor.

As soon as the end of the webbing is located, as above mentioned, the floor sections 3, 4, are forced down upon the webbing, Figures 4, 5, and 6, to anchor the same firmly 90 to the buckle frame, and thus effect a firmer grip thereagainst than would be possible with a series of teeth pierced from the floor.

When the floor sections are thus clamped 95 down against the webbing, the narrow openings *a*, *b*, will again appear to allow the webbing being partially drawn therein and thus give increased holding power thereto. These clearance spaces also prevent the lateral sides of the closing floor sections 3, 4, shearing the webbing. To enable the sections 3, 4, to lie level with the floor of the frame when depressed and thus prevent their edges 3^a and 4^a shearing the webbing against the walls 10 of the openings 5, 6, of the floor, each clamping floor section is shortened by 100 forcibly indenting said sections as at 11, Figures 10 and 11, so that the webbing is firmly compressed between the edges 10 and the ends of the sections 3, 4.

If desired, only one of the floor sections 3, Figure 12, could be employed, but the 110

end clearance spaces a must be provided as in the other views. This single clamping floor section will not require the bridge shown in the other views.

5 The indentation 13, Figs. 10 and 11, may also be formed in the narrow floor section 1^a to give additional strength thereto. The indentations 11 and 13 may both be used to widen the openings in the floor so that the 10 webbing will be caught between the ends of the clamping floor sections and the narrow floor section 1^a, as shown in Fig. 11.

14 represents the teeth of the lever 8.

Having thus described my invention what 15 I claim is:—

1. A buckle construction comprising a frame and a lever journaled thereto, said frame having a floor, elongated sections of the floor pierced therefrom to form clamping means for anchoring webbing to the 20 floor, means whereby said sections are reduced and made shorter than the openings in the floor from which said sections were

pierced, so that webbing can be secured between the ends of the sections and walls 25 of said openings.

2. A buckle construction comprising a frame and a lever journaled thereto, said frame having a floor with narrow initial 30 openings formed therein, webbing clamping sections pierced from the floor, the openings in the floor made thereby merging into the initial openings, and a section of the floor forming a bridge spanning said openings.

3. A buckle construction comprising a frame and a lever journaled thereto, said frame having a floor with spaced openings 35 therein, the floor between said openings sheared or pierced from the floor to form a clamp to secure a strip of webbing to the 40 floor, and said openings adapted to receive a portion of the webbing when the clamping section is depressed.

In testimony whereof I affix my signature.

WILLIAM E. HATHEWAY.
